BASE FOR ELECTRIC LAMPS AND SIMILAR
DEVICESWilliam G. Davis and Harry C. Atkins, Cleve-
land Heights, Ohio, assignors to General Elec-
tric Company, a corporation of New York

Application March 25, 1939, Serial No. 264,154

6 Claims. (Cl. 176—32)

Our invention relates to electric incandescent lamps, in general, and more particularly to bases for such lamps or similar devices and to a method of manufacturing the same.

5 The base construction commonly employed at present on electric incandescent lamps comprises a metallic shell or sleeve and a metallic center contact eyelet secured together by a button of insulating material. Heretofore, the base shells 10 have been formed from round blanks punched out of wide strip stock, the blanks being subsequently formed into a cylindrical shape by punch presses. With this method of manufacturing base shells, there is a considerable waste of the metallic 15 stock material from which the round blanks are punched, and a corresponding increase in manufacturing cost.

One object of our invention is to provide an improved method of manufacturing base shells 20 for electric incandescent lamps and similar devices which will eliminate practically all waste of the metallic stock material from which the bases are made and which will effect a material saving in the cost of manufacture.

25 Another object of our invention is to provide an improved base construction for electric incandescent lamps and similar devices.

Still another object of our invention is to provide an electric lamp base having a shell provided 30 with a longitudinally extending internal lamp seam joint which is discontinued for a short distance inward from the inner edge or rim of the shell to thereby permit proper application of the base onto the lamp bulb neck and in addition to 35 provide a slot through which one of the lamp leading-in wires may be led to the outer surface of the shell.

A further object of our invention is to provide an electric lamp base having a shell provided 40 with a plurality of relatively small embossments or protuberances arranged around said shell in the form of a helix with one or more of the embossments adjacent the rim of the shell displaced a relatively slight amount from the true 45 line of the helix to thereby provide means for locking the lamp in its socket.

Further objects and advantages of our invention will appear from the following description of species thereof and from the accompanying 50 drawing, in which:

Fig. 1 is a longitudinal sectional view of an electric incandescent lamp provided with a base comprising our invention; Fig. 2 is an elevation of the lamp shown in Fig. 1 taken at right angles thereto; Fig. 3 is a top view of the blank from

which the base shell comprising our invention is made; Fig. 4 is a side view of the base shell blank showing the manner in which the ends thereof are bent preparatory to the formation of the lap seam joint therebetween; Figs. 5 to 8 are 5 end views of the base shell blank showing the successive steps involved in rolling the blank into cylindrical shape and securing the abutting ends together by an internal lap seam joint; Fig. 9 is a fragmentary end view, on an enlarged 10 scale, of the base shell showing the completed internal lap seam joint; and Fig. 10 is an enlarged 15 elevation of a finished base shell comprising our invention.

Referring to the drawing, the lamp there 15 shown comprises a glass bulb or envelope 10 having a tapering neck portion 11 and an electric energy translation element in the form of a coiled or coiled coil filament 12 of refractory metal, preferably tungsten, hermetically sealed 20 therein. The said filament is supported within the bulb by a pair of leading-in wires 13, 14 connected to the opposite ends of the filament and having portions sealed into a pressed portion 15 of a stem 16. The filament 12 is further supported, at a point intermediate its ends, by a support wire 17 fastened to a cane rod 18 extending longitudinally of the lamp from the stem press 15. Additional support wires 19, 19 extend transversely from said cane rod 18 and engage 30 the leading-in wires 13, 14.

Secured to the neck portion 11 of the bulb 10, preferably by cement 20, is a base 21 according to our invention. The said base comprises a metallic shell 22, preferably of brass and having an inturned flange 23 at its dome end, and a metallic bottom contact eyelet 24 secured to said shell flange by a suitable insulating medium 25, such as glass. One leading-in wire 13 extends through a centrally located hole 26 in the base 40 insulation 25 and is connected to the bottom contact eyelet 24 preferably by solder 27, while the other leading-in wire 14 is bent back over the neck of the bulb and around the inner extremity or rim of the shell 22 where it is secured to the 45 same by solder 28.

As shown particularly in Figs. 2 and 10, the base shell 22 is formed with a plurality of outwardly extending protuberances or embossments 29 arranged around the circumference of the shell 50 in the form of a helix to thereby constitute an interrupted thread for engagement with the thread of a conventional lamp socket. The number and location of these protuberances along the line of the helix is immaterial, a sufficient 55

number, however, being provided adjacent the dome end of the base shell 22 to insure easy and positive threading of the lamp base in a conventional lamp socket. The protuberances 29 may be spherical in shape, as shown in the drawing, or they may be of any other suitable shape such, for instance, as a portion of a screw thread.

To provide means for locking the base in a socket, one or more of the protuberances 29 at the 10 inner end of the helix, i. e., adjacent the rim 33 of the base shell 22, may be displaced a slight amount, for instance, 0.010 of an inch or thereabouts, from the true line of the helix. The displacement may be to either side of the line of the 15 helix, i. e., towards the rim of the base shell or towards the dome thereof, as desired. The displaced protuberances force the other protuberances against the threads in the lamp socket during the last turn or so of the lamp into its 20 socket. The resulting tight frictional grip between the various base shell protuberances and the lamp socket threads thus provides a form of locking means tending to prevent any unscrewing action of the lamp in its socket which might 25 otherwise result from vibrations of various nature. The displacement of the protuberances, however, should not be so great as to prevent a complete insertion of the lamp base in its socket, otherwise the bottom center contact of the lamp 30 might not engage with the corresponding socket contact.

The base shell 22 according to the invention is formed from a blank 30 of metal (Figs. 3-4) which is first stamped with the protuberances 29 35 out of strip material, then rolled into cylindrical shape, and the abutting ends secured together by an internal lap seam joint 31, the successive steps being shown in Figs. 3 to 8. To insure proper fitting or alignment of the base shell on 40 the tapered neck 11 of the bulb, and further to provide a slit 32 through which leading-in wire 14 may be led to the outer surface of the base shell, the internal lap seam 31 is discontinued for a relatively short distance inward from the rim 45 33 of the base shell. For this purpose, the opposite ends of the metal blank 30 are provided with notches 34, 34 adjacent that edge 33 which eventually forms the rim of the base shell. The leading-in wire 14, outwardly of the base shell 50 22, is preferably disposed along the lap seam joint 31 and soldered thereto, the solder thus serving to further secure the ends of the metal blank together and to prevent disruption of the lap seam joint.

55 The rolling of the metallic blank 30 into cylindrical shape and the formation of the internal lap seam joint 31 is performed by a suitable machine, such as the multi-slide machine commercially used at present for the production of short 60 lengths of metallic tubing with internal lap seams. As shown in Fig. 9, the lap seam joint 31, when completed, consists of an inner hook or lip 35, formed by inwardly bending one end of the blank back upon itself, and interlocked with an inwardly offset hook or lip 36 on the other end of the said blank. Following the formation of the lap seam joint, the edge 37 of the cylindrical shell is rolled or bent inward to form 65 the flange or dome 23, thus completing the base shell. It is obviously desirable that none of the protuberances 29 be formed in the base at the 70 lap seam joint 31. Instead, they should all be located in spaced relation to said lap seam joint, otherwise the said joint might interfere with the

easy insertion or threading of the base shell into its socket.

By forming the base shells in the above-described manner there is a material saving in the amount of wasted metal, thereby resulting in an 5 appreciable saving in manufacturing cost over the method heretofore employed. Furthermore, the cost of die maintenance is considerably less for the improved method of manufacturing base shells. 10

While we have described our invention in connection with a base of the screw thread type, it is obvious that it may be applied equally as well to other types of bases such as, for instance, bayonet pin bases such as used on miniature 15 lamps. The pins are stamped in the metal blank from which the base shell is made in the same manner as the protuberances 29 referred to above. 20

What we claim as new and desire to secure by Letters Patent of the United States is:

1. A base for electrical devices comprising a shell, said shell consisting of a strip of metal formed in the shape of a cylinder with the abutting ends secured together by an internal lap 25 seam joint and having a plurality of socket-engaging protuberances disposed around its circumference, said protuberances being formed from the metal of said shell and being disposed in spaced relation to said lap seam joint. 30

2. A base for electrical devices comprising a shell, said shell consisting of a strip of metal formed in the shape of a cylinder with the abutting ends secured together by an internal lap seam joint and having a plurality of protuberances disposed around the circumference thereof in the form of a helix and in spaced relation to said lap seam joint. 35

3. A base for electrical devices comprising a shell having an open end, said shell consisting of a strip of metal formed in the shape of a cylinder with the abutting ends secured together by an internal lap seam joint and having a plurality of protuberances disposed around the circumference thereof in the form of a helix and in spaced relation to said lap seam joint, one or 40 more of said protuberances adjacent the said open end of said shell being offset a slight distance from the true line of the helix. 45

4. A base for electrical devices comprising a shell, said shell consisting of a strip of metal formed in the shape of a cylinder with the abutting ends secured together by an internal lap seam joint and having an outwardly projecting thread formed thereon, said thread being interrupted at said lap seam joint. 55

5. An electrical device comprising a bulb having a flared neck portion, an electric energy translation element sealed within said bulb, a pair of leading-in wires connected to said electric energy translation element and extending exteriorly of said bulb, and a base comprising a metallic shell portion secured at its rim to said flared bulb neck, said shell consisting of a strip of metal formed in the shape of a cylinder with the abutting ends secured together by an internal lap seam joint, said lap seam joint being discontinued at a relatively short distance from the rim of said shell to thereby provide a slit and to permit said rim to uniformly engage said flared bulb neck 65 around the periphery thereof so as to maintain alignment between said shell and bulb neck, one of said leading-in wires extending through said slit and being secured to said shell at said lap seam joint, and said shell having a plurality of 70

75 protuberances disposed around the circumference thereof in spaced relation to said lap seam joint. 75

socket-engaging protuberances disposed around its circumference.

6. An electrical device comprising a bulb having a flared neck portion, an electric energy translation element sealed within said bulb, a pair of leading-in wires connected to said electric energy translation element and extending exteriorly of said bulb, and a base secured to said bulb neck and comprising a metallic shell and a bottom contact eyelet secured together by insulation, one of said leading-in wires being con-

nected to said shell and the other of said leading-in wires being connected to said bottom contact eyelet, said shell consisting of a strip of metal formed in the shape of a cylinder with the abutting ends secured together by an internal lap seam joint and having a plurality of protuberances disposed around the circumference thereof in the form of a helix and in spaced relation to said lap seam joint.
